FRANZ KAŠPAR, OF OLMUTZ HODOLEIN, CZECHO-SLOVAKIA.

DEVICE FOR SEVERING AND APPLYING STAMPS OR THE LIKE TO ENVELOPS OR OTHER SURFACES.

1,388,817.

Specification of Letters Patent. Patented Aug. 23, 1921.

Application filed August 24, 1920. Serial No. 405,723.

To all whom it may concern:

Be it known that I, FRANZ KAŠPAR, a citizen of Czechoslovakia, resident of Olmutz Hodolein, Czechoslovakia, have invented 5 new and useful Improvements Relating to Devices for Severing and Applying Stamps or the like to Envelops or other Surfaces, of which the following is a specification.

This invention relates to devices for severing 10 stamps or the like from a rolled-up strip of indefinite length and applying them to envelops or similar surfaces at a single operation.

According to the invention, the device or 15 implement comprises a deppressible hand punch and a moistening attachment so arranged that by pressing down the punch the stamp strip, which has previously been fed forward, is automatically moistened; 20 the moistening attachment moving out of the path of the punch immediately the moistening operation has been completed, so that during the continued descent of the punch the cutting mechanism can be automatically 25 actuated to sever the stamp and permit its being applied to the envelop. During the succeeding upward movement of the punch, the various parts above mentioned are restored to normal position and mechanism is 30 automatically operated whereby the strip is advanced to bring the next stamp into position to be moistened when the punch is again depressed.

The invention resides in the particular 35 construction, combination and arrangement of parts whereby the above and other operations are automatically effected; an embodiment of the invention being illustrated in the accompanying drawings, in which:

40 Figure 1 is a part-sectional front elevation of the implement;

Fig. 2 is a vertical cross-section of the strip-feeding mechanism;

45 Figs. 3 and 4 are fragmental detail views showing two different positions of the moistening device and the operating lever to which it is connected;

Fig. 5 is a fragmental elevation at right angles to Fig. 1;

50 Fig. 6 is a detail view showing the mounting of the check pawl associated with the feed roller;

Figs. 7 and 8 are, respectively, a plan

view and a part-sectional side elevation of a table or support with which the implement 55 may be used; and

Fig. 9 is a detail view showing the construction and arrangement of the stop plate against which the punch-returning spring bears.

The improved implement consists mainly of two parts, viz: the frame 1 and the punch 2, the latter being mounted for vertical reciprocating movement within said frame.

To the frame there is affixed a horizontal pin 72 on which is fulcrumed the upper end of a lever 13 having spaced, upper and lower fingers 15 and 14, and also having an elongated lug 16; the upper finger 15 being provided with an inwardly-extending terminal 70 52. The pin 72 has coiled around it a compressed or tensioned spring 64 (Fig. 5) which presses lever 13 laterally against the frame, thus acting as a friction brake for said lever and, hence, for the moistening device 3 carried thereby. This device is in the nature of a lever which is hinged at one end to a horizontal pin 80 attached to the lower end of lever 13, and is pressed yieldingly upward by a torsion spring 60 coiled around 75 said pin. In its normal position, represented in Fig. 1, the lever is engaged by a detent 47 which catches under a roller 46 on the lever.

The frame 1 has adjustably connected to it a vertical rack 5 (Fig. 1) for actuating the hereinafter-described strip-feeding mechanism; and it also carries a removable liquid container 4 from which a wick 20 protrudes into position to contact with a 90 felt pad 22 carried by the lever 3, thereby providing a constant supply of moisture.

The punch 2 is provided with a guide-piece 57, which is mounted to slide in a slot 6 formed in the frame, and is further provided with a tubular stem 8 fitting in a guide sleeve 11 and terminating in a suitable knob or handle. The sleeve 11 is fixed to the frame and supports upon its upper edge the out-turned edge of a vertical arm 95 or extension 10' formed upon the edge of a horizontal stop plate 10 which is disposed within stem 8 (Figs. 1 and 9), said arm fitting in a longitudinal slot 8' with which said stem is provided. The stop plate 10 supports an expandible coil spring 9 (Fig.

- 1) serving to normally maintain the punch in elevated position; and a pad 61 may be employed to cushion the punch at the limit of its upward movement.
- 5 The moistener 3 is operated by the punch through the intermediary of a roller 12 attached to the guide 57 (Figs. 3 and 4); said roller being designed to travel along the inner edges of the fingers 15 and 14 on 10 the operating lever 13 which are so curved as to produce a swinging or rocking movement of said lever in one direction or the other, due to the pressure exerted thereagainst by the roller, according as the latter is engaged with the lower or the upper finger. The engagement of the roller with the lower finger is effected during the descent of the punch, as will be understood; but it does not take place until the last half of 15 the stroke, the roller traveling along the straight edge of the portion of the lever between the two fingers during the first half of the stroke, at which time the swinging movement of the lever is prevented by the engagement of the lug 16 with the in-turned end of a keeper 17 attached to the stud or axle whereon the roller turns. The keeper disengages said lug just about the time that the roller starts its movement along the 20 curved edge of the lower finger, and thereafter the lever is forced outwardly or away from the frame, moving from the position indicated in Fig. 3 to that indicated in Fig. 4; the provision of the lug and keeper thus avoiding premature movement of the 25 operating lever, which latter is stopped at the conclusion of its outward movement by the engagement of the terminal 52 of finger 15 with a lug 49 on the frame, and is retained in such position by the engagement 30 of the nose 19 on the moistener lever 3 with the detent 47 on the frame (Figs. 4 and 5).
- The operating lever remains in the position just mentioned during the first half 45 of the succeeding up-stroke of the punch, and until roller 12 strikes against the curved edge of the upper finger 15, whereupon the pressure exerted by the roller against said edge forces the lever to swing 50 back toward the frame into its original position.
- The strip 31 of stamps or the like is wound up on a suitable reel which is disposed within a drum or container 7 (Fig. 55 1) having a peripheral opening for the passage of the strip therethrough; said drum being provided with a spring tongue 59 which bears against the strip and thus tends to retard its feed movement. After leaving 60 the drum, the strip is led around a roller 78 (Figs. 1 and 2), constituting one element of the feed mechanism, and then passes successively through a resilient channel member 37 and through an opening formed in 65 the movable member or knife 51 of the cut-

ting or severing mechanism as subsequently explained, to a position beneath the presser pad or member 21 situated on the bottom of the punch. The feeding mechanism is mounted in the punch to move therewith; and its roller 78 has its heads 26 and 55 rigidly connected to a spindle 53^a (Fig. 2) which extends horizontally across the punch and is removably supported at one end by a bearing 54, the other end of the spindle 70 having a milled head 53. A pinion 25 in mesh with rack 5 is loosely mounted on the spindle between the roller head 26 and the adjacent wall of the punch and has pivoted to it a feed pawl 27 for engagement, under the influence of a spring 48 (Fig. 1), with the teeth 27^a formed internally on the aforesaid head 26. The other roller head 55 is provided with peripheral notches 63 (Fig. 6) engageable by a check pawl 29 controlled 75 by a spring 45 and pivoted on a screw 75 which is attached to the upper end of an angle lever 56 and moves in a guide slot in the punch wall; said lever being pivoted at its lower end on a screw 74 and being provided intermediate its ends with a clamping screw 65 which likewise extends through a guide slot in the punch wall. The mounting just described enables the feeding roller to be adjusted to a position in which, when 80 said roller is at rest and pawl 29 is engaged in one of the notches 63, the stamps or sections of paper will be severed exactly in the center of the separating lines of perforations by the cutting mechanism; it being understood that the screw 65 is tightened after the adjustment has been effected.

The body or circumferential wall of the roller is provided with pin points 30 (Fig. 2) disposed in rows for engagement in the perforations in the strip, the rows being spaced a distance apart equal to that between the rows of perforations in the strip, which latter is preferably pressed against the roller by means of an arcuate jaw 33 (Fig. 1) pivoted to a carrier 34 which is itself hinged to the frame. The said jaw is provided with internal grooves 36 to receive the ends of the pins 30 and is retained in its raised or operative position by means of a spring catch 35 connected to drum 7 and engageable with the carrier 34, as indicated in dotted lines in Fig. 1; but said carrier may readily be disengaged and swung downwardly into 105 its full-line position when the strip is to be initially passed around the roller.

The feeding mechanism operates substantially as follows:—During the descent of the punch, the roller 78 is held against rotation by the engagement of the check pawl 29 in the adjacent notch 63 in the roller head 55; and the pinion 25, which is constantly engaged with rack 5, turns loosely on spindle 53^a in a counter-clockwise direction 110 120 125 130

tion, its pawl 27 riding idly over the teeth 27^a on the other roller head 26, so that no movement of the strip will take place. When the punch is released and starts its 5 ascent, however, the pinion will be turned clockwise, whereupon its feeding pawl 27 is caused to engage the adjacent tooth 27^a and, in consequence, to positively drive the roller, with the result that the engagement 10 of the pin points in the perforations in the strip advances the latter; the check pawl being disengaged from its notch 63, as will be understood, but being thereafter engaged in the succeeding notch at the completion of 15 the movement of the punch.

The mechanism by which the stamps or sections of paper are severed comprises, in addition to the knife 51, a second knife 41 which is rigidly fixed to the punch, as will 20 be apparent from Fig. 1, and with respect to which the knife 51 is movable. The knife 41 terminates approximately flush with the under face of pad 21, but the movable knife 51 projects some distance below 25 said pad and is pressed yieldingly downward by the action of a spring 50 and, at the same time, is pressed against the fixed knife by means of suitable rollers 40 acted on by spring 50'. The spring 50 exerts its 30 downward pressure directly against a laterally projecting lug 73 (Fig. 1) which is integrally or otherwise rigidly connected with knife 51 and which has a depending finger 73' that rests upon the adjacent end of the 35 resilient channel member 37, the pressure of said spring 50 being sufficient to flex the channel member downward and thereby bring its mouth directly opposite the opening formed in knife 51, as shown in Fig. 5. 40 The member 37 is preferably constructed of thin flexible or resilient metal, and is fastened at its rear end by means of screws 37' or the like, to the punch. When the punch descends, the cutting mechanism 45 moves with it, the two knives remaining relatively stationary until the lower edge of knife 51 strikes against the wall of the support or table hereinafter mentioned. Thereafter, during the continued movement 50 of the punch, knife 51 will be forced upward against the action of spring 50, and as said knife yields, the channel member 37 also moves upward, carrying the strip with it into position to be ultimately severed by 55 the coaction between the two knives. During the subsequent return movement of the punch, the knife 51 is restored to its former position under the action of spring 50, and at the same time the resilient channel member 37 is again pressed down into position 60 by lug 73 to aline its mouth with the opening in said knife.

The implement as a whole may be advantageously employed in conjunction with 65 a support 42 (Figs. 7 and 8) constructed in

the form of a table, and is connected by means of depending legs 43 to a pair of superposed supporting arms 43^a. These arms are arranged below the table top and are pivoted for vertical swinging movement, 70 and they are normally held in raised position by means of springs 44^a; but the latter are somewhat weaker than the punch-operating spring 9, so that the imposition of pressure upon the punch will initially 75 effect the downward movement of the implement as a unit, and the actual movement of the punch itself will not take place until after the supporting legs 43 have completed their downward movement. When 80 the pressure upon the punch is removed, the springs 44^a will elevate the implement bodily, and thus move it above and out of the way of the previously stamped envelop, so that the envelops may therefore be 85 stacked up in a pile on the table, from which pile each envelop is removed after having been stamped. The table may further be provided with an adjustable gage 44 for the envelops, and with an adjustable vertical pin 67, the latter being engageable 90 in such a position that the stamps are applied to the envelops at the usual point.

In order to count the number of times 95 the implement has been used and, hence, the number of envelops stamped, there may be attached to the punch a suitable counter 57^a (Figs. 1 and 5) operated by means of a movable element 58 which is engageable 100 by a fixed lug 62 (Fig. 5) on the frame at each depression of the punch.

The complete operation, briefly stated, is as follows: During the first half of the down-stroke of the punch, the operating 105 lever 13 is held against movement by the engagement of the keeper 17 with lugs 16, and just when the disengagement of those two parts takes place, the roller 12 commences its travel along the curved upper edge of the 110 lower finger 14 on said lever. This has the effect of camming the lever outwardly of the frame 1 of the implement, during which movement the moistener 3 moves outwardly along with said lever, the pad 22 thereon being pressed against the under surface of the stamp by the action of the spring 60 and drawn along said surface. The outward movement of the lever continues until the pad has left the stamp and the nose 19 of the moistener has been brought into engagement 115 with the lip or detent 47 on the frame, the stopping of the lever being effected by the engagement of the terminal 52 with lug 49. During the continued movement of the 120 punch, the moistened stamp is pressed against the topmost envelop on the pile by the pad 21, and is severed from the strip by the coaction between the fixed and movable knives 41 and 51 as the latter knife ascends, 125 130

- the two operations taking place close together; and at the same time, the counter 57 is turned one step by the operating element 58 being engaged and shifted by the lug 62.
- 5 When the pressure upon the punch is removed, the spring 9 forces the punch upward, and during this stroke the movable knife 51 and the channel member 37 resume their former positions, while the pinion 25 positively drives the feed roller 78 and, hence, advances the strip 31 through the channel member and the opening in knife 51, the roller being arrested by the engagement of pawl 29 in the adjacent notch 63 at the 15 end of the movement of the punch. The operating lever 18, during the first part of the up-stroke of the punch, remains in the position into which it was moved during the preceding down-stroke of the punch; but during the last half of the up-stroke, the roller 12 on the punch engages the upper finger on the lever and thereupon forces the latter, and with it the moistener 3, to move inwardly toward the frame, this movement of the 25 moistener disengaging its nose 19 from the detent 47 which thereupon engages the roller 46 when the lever completes its inward movement. The implement is then ready for another operation.
- 30 I claim as my invention:—
1. An implement for affixing stamps and the like, comprising a frame; a depressible operating element movable therein; mechanism actuated by said operating element during its movement in one direction for feeding a strip of stamps; a rocking lever having a pair of opposed cams; a member on said operating element engageable with one cam during the descent of the operating element for rocking said lever in one direction, and engageable with the other cam during the ascent of the operating element for rocking the lever in the opposite direction; and a moistening device connected to said lever for operation thereby and adapted to be dragged along the gummed face of the stamp to be affixed during the movement of said lever in one direction. 105
  2. An implement for affixing stamps and the like, comprising a frame; a depressible operating element movable therein and having a stamp-applying member at its lower end; mechanism actuated by said operating element for feeding a strip of stamps through the frame toward said applying member; a rocking lever having a pair of opposed cams; a member on said operating element engageable with one cam during the descent of the operating element for rocking said lever in one direction, and engageable with the other cam during the ascent of the operating element for rocking the lever in the opposite direction; and a moistening device connected to said lever for operation thereby and adapted to be dragged along the 110
  3. An implement for affixing stamps and the like, the combination, with a depressible operating element, and stamp-feeding mechanism actuated thereby; of a rocking lever having a pair of opposed cam fingers; a member on said operating element engageable with one finger during the descent of the operating element to rock said lever in one direction, and engageable with the other finger during the ascent of the operating element to rock said lever in the opposite direction; and a moistening device 115 connected to said lever for operation thereby and adapted to be dragged along the gummed face of the stamp to be affixed during the movement of said lever in one direction. 120
  4. An implement for affixing stamps and the like, the combination, with a depressible operating element, and stamp-feeding mechanism actuated thereby; of a rocking lever having a pair of opposed cam fingers; a member on said operating element engageable with one finger during the descent of the operating element to rock said lever in one direction, and engageable with the other finger during the ascent of the operating element to rock said lever in the opposite direction; and a moistening device 125 connected to said lever for operation thereby and adapted to be dragged along the gummed face of the stamp to be affixed during the movement of said lever in one direction. 130

gummed face of the stamp to be affixed during the movement of said lever in one direction.

3. In an implement for affixing stamps and the like, the combination, with a depressible operating element, and stamp-feeding mechanism actuated thereby; of a rocking lever having a pair of opposed cam fingers; a member on said operating element engageable with one finger during the descent of the operating element to rock said lever in one direction, and engageable with the other finger during the ascent of the operating element to rock said lever in the opposite direction; and a moistening device 70 connected to said lever for operation thereby and adapted to be dragged along the gummed face of the stamp to be affixed during the movement of said lever in one direction. 75

4. In an implement for affixing stamps and the like, the combination, with a depressible operating element, and stamp-feeding mechanism actuated thereby; of a rocking lever having a pair of opposed cam fingers; a member on said operating element engageable with one finger during the descent of the operating element to rock said lever in one direction, and engageable with the other finger during the ascent of the operating element to rock said lever in the opposite direction; and a moistening device 80 connected to said lever for operation thereby and adapted to be dragged along the gummed face of the stamp to be affixed during the movement of said lever in one direction. 85

5. In an implement for affixing stamps and the like, the combination, with a depressible operating element, and stamp-feeding mechanism actuated thereby; of a rocking lever having a pair of opposed cam fingers; a member on said operating element engageable with one finger during the descent of the operating element to rock said lever in one direction, and engageable with the other finger during the ascent of the operating element to rock said lever in the opposite direction; and a moistening device 90 connected to said lever for operation thereby and adapted to be dragged along the gummed face of the stamp to be affixed during the movement of said lever in one direction. 95

6. In an implement for affixing stamps and the like, the combination, with a depressible operating element, and stamp-feeding mechanism actuated thereby; of a rocking lever having a pair of opposed cam fingers; a member on said operating element engageable with one finger during the descent of the operating element to rock said lever in one direction, and engageable with the other finger during the ascent of the operating element to rock said lever in the opposite direction; and a moistening device 100 connected to said lever for operation thereby and adapted to be dragged along the gummed face of the stamp to be affixed during the movement of the lever in one direction, said device having a spring associated with it for swinging it toward the stamp. 105

5. In an implement for affixing stamps and the like, the combination, with a depressible operating element, and stamp-feeding mechanism actuated thereby; of a rocking lever provided with a pair of opposed cams; a member carried by the operating element and engageable with one cam during the descent of said element to rock the lever in one direction, and engageable with the other cam during the ascent of the operating element to rock said lever in the opposite direction; and a moistening device 110 connected to the lever and adapted to be moved across the gummed face of the stamp to be affixed during the movement of the lever in one direction; and means on one of said cams for arresting the lever after it has traveled a predetermined distance in one direction. 115

6. In an implement for affixing stamps and the like, the combination, with a frame, a depressible operating element mounted therein, and stamp-feeding mechanism actuated by said element; of a rocking lever provided with a pair of opposed cams, one of which has an offset terminal; a member 120

- carried by the operating element and engageable with said cam during the descent of said element to rock said lever outwardly of the frame, and engageable with the other 5 cam during the ascent of the operating element to return said lever to initial position; a moistening device operatively connected to said lever and adapted to be moved across the gummed face of the stamp to be affixed 10 during the movement of the lever in one direction; and a stop fixed to the frame for engagement by said cam terminal to limit the outward movement of the lever.
7. In an implement for affixing stamps 15 and the like, the combination, with a depressible operating element and stamp-feeding mechanism actuated thereby; of a rocking lever provided with a pair of opposed cams and with a lug; a member carried by the operating element and engageable with one cam at a predetermined point in the descent of said element to rock said lever in one direction, and engageable with the other cam during the ascent of said element to rock the lever in the other direction; a keeper on the operating element adapted to engage said lug during the first portion of the descent of said element to retain said lever in its initial position, and to release 25 the lug when the operating element reaches the said point in its descent to permit the rocking movement of the lever; and a moistening device connected to said lever for operation thereby and adapted to be dragged 30 along the gummed face of the stamp to be affixed during the movement of said lever in one direction.
8. In an implement for affixing stamps and the like, the combination, with a depressible operating element and stamp-feeding mechanism actuated thereby; of a rocking lever provided with a pair of opposed cams; a member carried by the operating element and engageable with one 45 cam at a predetermined point in the descent of said element to rock said lever in one direction, and engageable with the other cam during the ascent of said element to rock the lever in the other direction; means for automatically locking said lever against movement until the operating element reaches the said point in its descent, said means thereafter releasing the lever to permit its movement; and a moistening device 50 connected to said lever for operation thereby and adapted to be dragged along the gummed face of the stamp to be affixed during the movement of said lever in one direction.
- 55 9. In an implement for affixing stamps and the like, the combination, with a depressible operating element and stamp-feeding mechanism actuated thereby; of a rocking lever provided with a pair of opposed cams; a member carried by the operating element and engageable with one cam at a predetermined point in the descent of said element to rock said lever in one direction, and engageable with the other cam during the ascent of said element to rock the lever in the other direction; means for automatically locking said lever against movement until the operating element reaches the said point in its descent, said means thereafter releasing the lever to permit its movement; and a moistening device connected to said lever for operation thereby and adapted to be dragged along the gummed face of the stamp to be affixed during the movement of said lever in one direction.
- 60 10. In an implement for affixing stamps and the like, the combination, with a frame, a depressible operating element mounted therein, and stamp-feeding mechanism actuated by said element; of a rocking lever provided with a pair of opposed cams and with a lug, one cam having an offset terminal; a member carried by the operating element and engageable with said cam at a predetermined point in the descent of said element to rock the lever outwardly of the frame, and engageable with the other cam during the ascent of said element to return said lever to initial position; a keeper on the operating element adapted to engage said lug during the first portion of the descent of said element to retain the lever in its initial position, and to release the lug when the operating element reaches the said point in its descent to permit the outward movement of the lever; a moistening device operatively connected to said lever and adapted to be moved across the gummed face of the stamp to be affixed during the movement of the lever in one direction; and a stop fixed to the frame for engagement by said cam terminal to limit the outward movement of the lever.
- 65 11. An implement for affixing stamps and the like, comprising a frame; a depressible operating element movable therein; mechanism actuated by the operating element during its movement in one direction for feeding a strip of stamps toward said element; cutting mechanism for severing a stamp from the strip at each depression of said element; said mechanism embodying a pair of knives arranged face to face and connected to said element to move therewith, one knife being movable relatively to the other and having an opening for the passage of the strip therethrough, and a spring bearing against the movable knife to cause it to project below the other knife, said movable knife adapted to be forced upward at one point in the descent of the operating element to effect the cutting operation; and means

for automatically moistening the stamp to be affixed prior to its being severed from the strip; said operating element having an affixing member connected to its lower end.

- 5 12. An implement for affixing stamps and the like, comprising a frame; a depressible operating element movable therein; mechanism actuated by the operating element during its movement in one direction for feeding a strip of stamps toward said element; cutting mechanism for severing a stamp from the strip at each depression of said element, connected to the latter to move therewith; a flexible channel member interposed between the feeding and cutting mechanisms for directing the strip to position to be acted on by the cutting mechanism, said member being adapted to yield during the movements of the operating element; and 10 means for automatically moistening the stamp to be affixed prior to its being severed from the strip; said operating element having an affixing member connected to its lower end.
- 15 13. An implement for affixing stamps and the like, comprising a frame; a depressible operating element movable therein; mechanism actuated by the operating element during its movement in one direction for feeding a strip of stamps toward said element; cutting mechanism for severing a stamp from the strip at each depression of said element; said mechanism embodying a pair of knives arranged face to face and connected to said element to move therewith, one knife being movable relatively to the other and having an opening for the passage of the strip therethrough, and a spring bearing against the movable knife to cause it to 20 project below the other knife, said movable knife adapted to be forced upward at one point in the descent of the operating element to effect the cutting operation; a flexible channel member interposed between the 25 feeding and cutting mechanisms and having its mouth constantly disposed in alinement with the opening in the movable knife to guide the strip therethrough, said member being adapted to yield during the movements of the operating element; and means for automatically moistening the stamp to be affixed prior to its being severed from the strip; said operating element having an affixing member connected to its lower end.
- 30 14. An implement for affixing stamps and the like, comprising a frame; a depressible operating element movable therein; a rack fixed to the frame; strip-feeding mechanism

carried by the operating element to move therewith and embodying a feed roller 60 around which the strip passes, a normally-loose pinion at one end of the roller constantly meshing with said neck, and means for automatically coupling said pinion to said roller to rotate the same during the 65 movement of the operating element in one direction only; means actuated by said operating element for severing a stamp from the strip at each movement of said element in one direction; and means for automatically 70 moistening the gummed face of the stamp before being severed.

15. An implement for affixing stamps and the like, comprising a frame, a depressible operating element movable therein; a rack 75 fixed to the frame; strip-feeding mechanism carried by the operating element to move therewith and embodying a feed roller around which the strip passes, a normally-loose pinion at one end of the roller constantly meshing with said rack, means acting automatically to couple said pinion to said roller to rotate the same during each ascent of said operating element, and to uncouple it from said roller during each descent, and means for positively holding said roller against rotation while uncoupled; means actuated by said operating element for severing a stamp from the strip at each 80 movement of said element in one direction; and means for automatically moistening the 85 gummed face of the stamp before being severed.

16. An implement for affixing stamps and the like, comprising a frame; a depressible 90 operating element movable therein, mechanism, including a roller for feeding a perforated strip of stamps through the frame at each movement of the operating element in one direction, said roller having rows 100 of pin points to engage in the perforations in the strip; a movable arcuate jaw for holding the strip against said roller, said jaw adapted to fit against the roller and having grooves for the reception of said points; means actuated by said operating element for severing a stamp from the strip at each 105 movement of said element in one direction; and means for automatically moistening the gummed face of the stamp before being 110 severed.

In testimony whereof I affix my signature.

FRANZ KAŠPAR.

Witness:

HUGO JASS.
